Frederick H. Arnold, Inventor

By Attorney

UNITED STATES PATENT OFFICE.

FREDERICK H. ARNOLD, OF READING, PENNSYLVANIA.

GATE-PATTERN.

SPECIFICATION forming part of Letters Patent No. 731,738, dated June 23, 1903.

Application filed January 3, 1903. Serial No. 137,659. (No model.)

To all whom it may concern:

Be it known that I, FREDERICK H. ARNOLD, a citizen of the United States, residing at Reading, in the county of Berks and State of Pennsylvania, have invented certain new and useful Improvements in Gate-Patterns; and I do hereby declare the following to be a full, clear, and exact description of the invention, such as will enable others skilled in the art to 5
10 which it appertains to make and use the same.

This invention relates to improvements in gate-patterns; and the object is to provide a device by the use of which the dross and dirt contained in the molten metal may be 15
20 completely screened and prevented from entering the casting, thus permitting a thinner flow of metal than would otherwise be possible and preventing rough or spongy surfaces on the casting due to foreign substances in the metal.

To this end my invention consists in the details of construction, as hereinafter more fully described and claimed, and clearly illustrated in the accompanying drawings, in 25
30 which—

Figure 1 is an end view, and Fig. 2 a plan view, of a portion of a pattern-gate with my invention shown thereon.

Referring more particularly to the drawings, the numeral 1 designates the main gate-pattern, which may be of any desired shape and has, as usual, a number of smaller or feed gate-patterns 2, which extend from openings in the sides of the main gate-pattern above 35
40 the base thereof, so that any metal poured into the main gate-pattern will strike the bottom thereof and divide itself, thereby flowing gradually or by means of gravity through the feed gate-patterns 2 in opposite directions, so as to prevent the dross and dirt from being forced into the pattern 5. In my present construction I have formed these feed gate-patterns 2 at a slight downward angle from their point of connection to the main portion 45
50 1, so that the base of said main portion will be somewhat higher than a horizontal base-line drawn from the lower end of the small gate-pattern 2 on one side to the same points of the pattern on the other side. This will insure a free flow of the molten metal down the inclined portions to all parts of the mold. These feed-patterns 2 are tapered toward their outer ends,

and the outer corner of the upper face of each pattern is removed, so as to form a shoulder 3. From this shoulder the end is curved, as 55
60 65 at 4, in an oblique direction toward the lower and outer extremity to form a reduced narrow portion where they join the casting-pattern. The corner 3 checks the flow of the upper portion of the molten metal and catches 60
65 and retains all the dross and drift contained therein as it passes toward the impression made in the mold by the pattern 5, and the curved end 4 will insure the easy flow of the metal, which being cleaned of all dross and 70
75 foreign substance is practically a pure metal and will not only flow freely, but will pass from the gates in a fine stream, and thus permit a much thinner casting than would otherwise be possible. This screening of the dross from the metal will prevent all so-called "sand-holes" and "spongy surfaces," which in reality are usually caused by dross or foreign substances in the metal. The screening is effectually accomplished by my present construction, as the foreign substances in the metal being lighter than the metal itself will ride 75
80
85 on the surface, and as it reaches the shoulder 3 in the feed-gates it will be arrested and prevented from passing into the casting proper; but the pure metal flowing beneath will pass out freely and in a fine stream, thus insuring clean perfect castings.

It will be noticed that the point of connection between the gates and the castings is not thickened, as the dross is taken from the metal immediately before it reaches this point, leaving the point of junction thin and easy to sever.

By the use of my invention the metal will 90
95 have no tendency to chill before reaching its destination, as the volume is kept comparatively large and bulky until just prior to its entering the casting—that is, just as it leaves the curved ends of the gates 2—and then it will be purified and can flow more freely than metal that has not been screened.

Having thus fully described my invention, what I claim, and desire to secure by Letters Patent, is—

1. A device of the class described, comprising a main gate-pattern and a plurality of outwardly and downwardly inclined feed-gate-patterns extending from the sides thereof and

independent of the base of said main gate-pattern, the outer corner of the upper portion of said feed gate-patterns being removed to form a reduced lower extremity.

- 5 2. A device of the class described, comprising a main gate-pattern and a plurality of downwardly-inclined tapering feed gate-patterns radiating from the sides thereof and independent of the base of the main gate-pattern, said feed gate-patterns each being pro-

vided with a shoulder on their upper face, and a curved end extending obliquely from said shoulder toward the base to form a reduced outer extremity.

In testimony whereof I affix my signature 15 in presence of two witnesses.

FREDERICK H. ARNOLD.
